UNITED STATES PATENT OFFICE.

JAMES E. DOYLE, OF CLEVELAND, OHIO.

METHOD OF AND MEANS FOR HEATING PRINTED SHEETS.

1,405,506.

Specification of Letters Patent. Patented Feb. 7, 1922.

Application filed November 11, 1919. Serial No. 337,273.

To all whom it may concern:

Be it known that I, JAMES E. DOYLE, a citizen of the United States, residing at Caxton Building, in the city of Cleveland, county of Cuyahoga, and State of Ohio, have invented a new and useful Improvement in Methods of and Means for Heating Printed Sheets, of which the following is a specification, the principle of the invention 10 being herein explained and the best mode in which I have contemplated applying that principle, so as to distinguish it from other inventions.

My invention relates broadly to the means 15 for and the method of conditioning paper either before or after printing thereon, and more particularly comprehends the application of heat from a glowing or incandescent material so as to more effectively remove static electricity and dry the sheet of 20 paper. The drawings exemplify the use of my invention with freshly printed sheets.

I am well aware that the prior art both 25 printed and practiced has been steadily developing during the last decade, as is evidenced by the following U. S. patents:—

Hergesheimer, 897,831, of Sept. 1st, 1908; Daningburg, 978,704, of December 3, 1910; Mortimer, 1,037,960, of Sept. 10, 1912; Spurrier, 1,050,399, of January 14, 1913; Doyle, 1,222,746, of April 17, 1917, and my later pending application filed August 17, 1918, Serial No. 250,391.

I have discovered that the most successful application of heat to a paper sheet is 35 by means of a glowing or incandescent body, while progressively different areas of the paper sheet are momentarily allowed to nearly or even actually contact, during relative movement therebetween. Such an incandescent source of heat is best created by 40 means of an electric current passed through a suitable resistance element which is either moved across the surface of the sheet or else 45 the sheet is drawn over the glowing surface. My invention may be adapted to employment in conjunction with any kind of machine which conveys paper and therefore to various locations on machines used in the 50 printing industry, for instance, at the delivery end of a cylinder press, on a substantial level with the diagonal feed rollers over which a paper sheet is conveyed so that it will move in engagement with a lateral

guide preparatory to being folded and in 55 association with what is known as a Miller feed on a Gordon type of press.

Figure I is a plan view showing my invention interposed between the delivery end of a printing press and diagonally arranged 60 feed rollers for continuing the conveyance of the sheet along a lateral guide toward a folding machine.

Figure II is a side elevation of the same.

Figure III is a diagrammatic view, partly 65 in elevation and partly in section, showing a modified application of my invention at two places to the delivery end of a cylinder press.

Figure IV is an enlarged broken plan view 70 of my composite heating construction attached to it.

Figure V is a side elevation of Figure IV.

Figure VI is a still further enlarged plan view of the support having a single heating 75 element.

Figure VII is a side elevation of Figure VI.

Figure VIII is a section on line VII—VII of Figure V.

Figure IX is an enlargement of a section on line IX—IX of Figure IV looking in the direction of the indicating arrows.

Figure X is a section on line IX—IX of Figure IV, correspondingly enlarged.

Figures XI to XIV inclusive are diagrammatic views of the electric wiring system showing four different positions of a three-way switch.

Mounted ahead of a feed roller frame 1 90 are shafts 2 and 3 carrying rolls 4 and 5 respectively, between which a printed paper sheet P is delivered from a printing press. At the other end of the frame 1 are a pair of shafts 6 and 7 supported on a folding 95 machine not shown, and carrying rolls 8 and 9 respectively. Along the upper edges of the sides of the frame 1 are plurality of angularly disposed brackets 10 fashioned with tapped openings 11 in diagonally opposite pairs of which screws 12 are placed, upon which the ends of metal feed rollers 13 are mounted. As appears in Figure I the rollers 13 are necessarily of varying length and are to be assumed as rotating by some 100 means not shown.

On one side, the frame 1 carries a pair of brackets 14 through which set screws 15 pass.

These screws have knurled ends 16 enabling manual adjustment of brackets 17 carried by a lateral guide 18 which extends along the left side of the frame 1 with reference to the direction of movement of the paper sheet. The guide 18 has an overhanging upper edge 19 carrying an extension 20 beneath which the sheets are to move. The action of the rolls 13 tend to move the paper sheets laterally as indicated by the dotted lines until they engage the guide 18 so that they will all reach the same prescribed position between the rolls 8 and 9 preparatory to becoming folded.

15 My composite incandescent heater is secured to the frame extension 22 at two places by means of bolts 23 which are also secured to a secondary heater support 24 by means of bolt and nut combinations 25 as appears in Figure IX. Secured in any suitable manner, as by rivets 27, to a laterally projecting end of the support 24 is a U-shaped receptacle 26 in which a plurality of superimposed porcelain units are fitted. 20 The drawings, and particularly Figure IV exemplify four distinct superimposed pairs A, B, C and D arranged in a row in the receptacle 26. Inasmuch as the construction is the same for each, only one pair need be described. Directing attention to Figure X it will be seen that a lower porcelain member 28 is provided with four longitudinally extending channels 29 while the upper porcelain member 30 is similarly fashioned with 35 four longitudinally extending channels 31 which are opened above. At one end of the upper porcelain member 31 are two permanently imbedded duplex binder posts projecting both above as screws 32 and below as perforate brass ends 33 into which latter the end of a copper lead wire 34 is brazed. The lead wire 34 occupies each of the channels 29 and is electrically connected up through the posts with a resistance coil 35 40 which zig-zags through each of the channels 31. The middle bend 36 of the resistance coil 35 is clearly shown in Figure IX. It should be understood that when the electric current is allowed to flow through the wire 34 and coil 35 the latter will glow or become 45 intensely incandescent.

At each set of meeting ends of the pairs of porcelain members 28 and 30, I provide inverted U shaped covers 37 adapted to have 50 telescopic fit over short lengths of the receptacle 26 and to be secured in place by means of screws 38.

The operation of my composite heating unit is controlled by a pair of three-way 55 switches 39 and 40 which receive current through a cable 41. Since nothing is claimed for the switch construction it need not be further described. The operation is clearly shown in the diagrammatic Figures XI to 60 XIV; Figure XI showing both coils off,

Figure XII showing the first coil on and the second off, Figure XIII showing the first coil off and the second on, and Figure XIV showing both coils on. It being assumed that all of the four coils A, B, C and D are 70 cold the first snap turn of the switch 39 energizes the coil B and the first snap turn of the switch 40 likewise energizes the coil C. The next snap turns of the switches 39 and 40 bring on the coils A and D to a glowing 75 heat respectively. Thus all of the coils may be off, all the coils may be on or the two middle coils B and C may alone be heated, which middle localization of heat is frequently all that is required. 80

The modification of Figure III shows the use of my invention at two places, and the designating numerals for the same parts are each one hundred more than in my Patent No. 1,222,746. Only cursory identification 85 will be made of the essential supporting parts of the printing press and some other parts which aid in disclosing the method of applying my invention. That much of the frame of the printing press which is 90 shown in Figure III is designated by the numeral 101 and includes an extension above the cylinder 102. The bed 103 is shown below and upon the same a plurality of linking rolls 104 are visible. Rotatably 95 mounted upon the over-hanging portion 101 and a portion of the frame removed forwardly therefrom are a pair of rollers 105 and 106 respectively. Those rollers actuate the conventional type of tape conveyer 100 107, the upper portion of which is designed to travel in a direction away from the cylinder. Positioned somewhat farther beyond and in the direction of travel of the conveyer 107 is a deposit table 108. The upper surface of this table is provided near its outer edge with an abutting rail 109. Disposed above the table 108 and inclined upwardly toward the cylinder are a pair of 110 lateral supporting members 110 which incidentally answer as guides for the side edges of the moving paper sheets.

A gripping device whose function consists in carrying paper sheets forwardly beyond the location of the roller 106 will now 115 be described. Generally speaking, it involves a traveling carriage provided with gripping fingers and a pair of linked arms capable of reciprocating it when actuated in a manner not shown since common to 120 the art. One arm 111 is pivotally mounted to the frame 112. The free extremity of the arm 111 articulates through the medium of a pivot pin 113 with the second arm 114, and the extremity of this arm 125 articulates in a similar manner through the medium of a pin 115 with the carriage 116. The carriage 116 involves in its construction forwardly and rearwardly disposed rollers 117 which are adapted to travel 130

upon the members 110. Intermediately of the rollers 117 the carriage is provided with an oscillating rod 118 extending transversely in the direction which the paper sheet is to follow. The rod 118 supports a plurality of gripping fingers 119 which are in Fig. III shown in their elevated position. This position they assume automatically and in a manner also well known to such as are conversant with the art, when the carriage is returning, as indicated by the arrow, in the direction of the conveyer 107. The carriage 116 is provided with a depending bracket 120 which supports a rod 121 extending between the members 110. Secured along the rearward portion of the rod 121 and fixedly maintained in an inclined position are a plurality of alined arms 122. These arms constitute a movable table upon which the sheet of paper P is supported during transit.

At other points along the rod 121 I support the structure H embodying my present invention so as to in turn position it just beyond and at a somewhat higher level than the top surfaces of the arms 122. Such supporting agencies consist of suitable clamps 123. It will be noticed also in Figure III that I have shown my type of incandescent heater H at another and fixed point ahead of the traveling carriage with reference to the direction of delivery of the sheet, in which location the sheets pass over the heater, instead of the heater being drawn back under the sheet.

I claim:—

1. The method of conditioning freshly printed paper, which consists in conveying the sheet and causing an incandescent heat to be applied thereto along a line extending diagonally within the mean plane of the passing portion of said sheet.

2. The method of conditioning freshly printed paper, which consists in conveying the sheet and causing an incandescent heat to be applied thereagainst along an oblique line within the mean plane of the passing portion with reference to the direction of travel of said sheet.

3. The method of conditioning freshly printed paper, which consists in conveying the sheet in a given direction and opposing lineal heat thereacross, such heat being ap-

plied in a direction oblique with respect to the direction of travel of said paper and so as to be contacted thereby.

4. The method of conditioning a paper sheet after printing thereon, which consists in moving said sheet diagonally across the line of extent of a glowing surface.

5. The method of conditioning a sheet after printing thereon, which consists in conveying said sheet in direction, diagonally across a line of incandescence.

6. The combination with means for conveying a paper sheet, means for folding the same and interjacent means for causing one edge of said sheet to follow a given line, of an incandescent surface arranged in opposition to said edge aligning means.

7. The combination with a roller for conveying a paper sheet, of a heater arranged at an angle to the axis said roller.

8. The combination with a series of rollers for conveying a paper sheet and a wall raised above the upper surface of said rollers and extending at an angle to the axes thereof, of a heater extending at an angle to the axes of said rollers.

9. The combination with a series of rollers for conveying a paper sheet and a wall raised above the upper surface of said rollers and extending at an angle to the axes thereof, of an incandescent member extending at an angle to the axes of said rollers and in contactual proximity to said moving sheet.

10. Means for heating printed sheets comprising the combination with a conveyer, of a series of electrical units arranged end to end across the route of travel of said sheet upon said conveyers, and means for energizing one or more of said units whereby to enable restriction of the application of heat within lateral limits.

11. Means for heating printed sheets comprising the combination with means for moving a sheet, of a series of electrical units arranged in a row extending at an angle to the direction of travel of said sheet at the moment of its closest approach to said units and a switch control for energizing different combinations of said units whereby the application of heat may be restricted to a predetermined area of the passing sheet.

Signed by me, this 5th day of Nov., 1919.
JAMES E. DOYLE.
